UNITED STATES PATENT OFFICE

126,506

DESIGN FOR A MINIATURE ELECTRIC LAMP SOCKET

Jasper Derry, Medford, Mass., assignor to Terkel-
sen Machine Company, Boston, Mass., a corpo-
ration of Massachusetts

Application January 30, 1941, Serial No. 98,527

Term of patent 7 years

To all whom it may concern:

Be it known that I, Jasper Derry, a citizen of the United States of America and a resident of Medford, in the county of Middlesex, Commonwealth of Massachusetts, have invented a new, original, and ornamental Design for a Miniature Electric Lamp Socket, of which the following is a specification, reference being had to the accompanying drawing, forming part thereof.

In the drawing:

Fig. 1 is a plan view of a miniature electric lamp socket showing my new design; and

Fig. 2 is a side elevational view.

I claim:

The ornamental design for a miniature electric lamp socket, substantially as shown.

JASPER DERRY.
